(57) **CLAIM**

The ornamental design for a headset, as shown and described.

DESCRIPTION

FIG. 1 is a front view of an embodiment of a headset; FIG. 2 is a rear view of the headset shown in FIG. 1; FIG. 3 is a right side view of the headset shown in FIG. 1; FIG. 4 is a left side view of the headset shown in FIG. 1; FIG. 5 is a top view of the headset shown in FIG. 1; FIG. 6 is a bottom view of the headset shown in FIG. 1; and, FIG. 7 is a perspective view of the headset shown in FIG. 1. The uneven broken line immediately adjacent to the shaded area represents the bounds of the claimed design. All other uneven broken lines represent the remaining portion of the headset. The broken lines in FIGS. 1 through 7 are for environmental purposes only and do not form any part of the claimed design.

1 Claim, 7 Drawing Sheets
